UNITED STATES PATENT OFFICE.

HARRY W. DENHARD, OF SAN FRANCISCO, CALIFORNIA, ASSIGNOR TO GEORGE B. KATZENSTEIN, JR., OF SAN FRANCISCO, CALIFORNIA.

ELECTRIC HEATER.

938,127.

Specification of Letters Patent. Patented Oct. 26, 1909.

Application filed June 25, 1908. Serial No. 440,371.

To all whom it may concern:

Be it known that I, HARRY W. DENHARD, a citizen of the United States, residing at San Francisco, in the county of San Francisco, State of California, have invented certain new and useful Improvements in Electric Heaters, of which the following is a specification.

This invention relates to the heating of water, and is designed to provide a heater of simple and compact construction, adapted to heat the water electrically and utilizing the water or other liquid to furnish the necessary resistance to produce the heat, the water in the heating chamber surrounding the electrodes and forming the connection between the positive and negative electrodes, and in the crossing of the water space or spaces the current heats the water. This enables an automatic action to take place without injury to the heater when the water supply is cut off or ceases from any cause, for the reason when there is no water or liquid in the heating chamber the circuit is broken and the heating action ceases.

The invention is not limited to the particular form of device illustrated in the accompanying drawings, as it is susceptible of many modifications, as will be readily apparent, and the drawings are intended only to illustrate the broad subject matter.

In the drawings,—Figure 1 is a longitudinal section through the heater. Fig. 2 is a cross section. Fig. 3 is a detail.

In Fig. 1, an outer inclosing cylinder, preferably of metal shown at 1, is tubular, and closed at its ends by caps 2—3, held in place by screws or other suitable fastening devices 4. The cap 2 has a projecting hollow stem 5 having a screw threaded, or other suitable connection with a liquid supply pipe 6. The cap has a post and nuts 7 for the electrical connections and metallic contact is made between this post and the plate 8, which is provided with sockets or recesses to receive the ends of electrodes 9, three being shown, though the number may be increased or diminished, as desired. Above the metallic plate 8 is a rubber disk 10 which receives the end of a porcelain cylinder 11, forming the water chamber and providing non-corrosive material so as to prevent any contamination of the water. Precisely the same construction is provided at the opposite end of the cylinder except

that the electrodes 9, three in number in the drawings, do not extend all the way through, but have their ends seated in pockets 11, of non-conducting material, such as porcelain, while the electrodes extending from the upper end are fitted in like manner to like pockets. The metallic contact plate 8 has a rubber gasket 13 above it and a like gasket 12 below it, so that the plate is insulated above and below. The electrode support 11 is held in place upon the plate 8 by a screw 14 or other suitable fastening device, passing through the plate and entering the support. This support, as has been stated, is composed of non-conducting material, and as shown in Figs. 2 and 3, is provided with three openings passing entirely through from top to bottom and three pockets or recesses which pass only partially through. The effect of this is to allow three of the electrodes to pass through the support to contact with the metallic plate and to enter the recesses therein, while the opposite ends of these electrodes pass into the pockets of the electrode support and have no connection with the metallic plate at that end. In other words, three of the electrodes have connection with the metallic plate at one end and three at the other end, while the opposite ends do not pass all the way through, but are supported in the recesses or pockets.

The water is allowed into the chamber through the inlet pipe 6 and forms the connection between the electrodes forming a resistance and in the passage of the current from one set of electrodes to the other the resistance offered by the water generates the heat and the water is thereby heated. Any number of electrodes may be utilized and these may be placed at any suitable distance apart so as to increase or diminish the resistance. The water passes out through the pipe 15 and the heater may be utilized in connection with a small reservoir of water so as to heat it rapidly and thus provide a permanent supply of heat and water.

The invention is not limited to the use of the heater for water alone, but may be utilized for heating any liquid.

The electrodes may be of any shape.

When water is to be heated to be used for domestic purposes it is preferred to make the electrodes of carbon, but these electrodes may be of metal and thus reduce the liability of breakage.

I do not limit myself to the independent porcelain chamber described and shown, as the same end may be attained by enameling the inside of the metal casing.

5 What is claimed is:—

1. In an electrical heater, a fluid chamber, a positive electrode therein, one end being supported in electrical connection and the opposite end having an insulated support, a negative electrode having an electrical connection and support at one end and an insulated support for the opposite end, an inlet or outlet for a suitable liquid, the said liquid furnishing the necessary resistance, substantially as described.
- 10 2. In an electrical heater, the casing, having its end closed by caps, binding posts

supported by said caps, a non-corrosive cylinder within the casing forming a liquid chamber within the cylinder, electrodes supported within said space in two groups, one group being supported from one cap, and the other from the opposite cap, the groups being separated and insulated from each other, and the inlet and outlet for the water, 25 substantially as described.

In testimony whereof I have affixed my signature in the presence of two witnesses this 12th day of June 1908.

HARRY W. DENHARD.
